TUNER

Fred Woods, Richmond, Surrey, England, assignor to Radio Corporation of America, a corporation of Delaware

Application December 29, 1931, Serial No. 583,631
In Great Britain December 29, 1930

15 Claims. (Cl. 171—119)

This invention relates to radio and other high frequency receivers, and more particularly to so-called multi-range receivers, i. e. receivers adapted to be operated over a plurality of tuning ranges.

The invention has for its object to provide a multi-range radio or other high frequency receiver, whereby the necessary switching operations to change the receiver over from one wave length range to another may be effected in a simple and rapid manner, and wherein the number of external connections necessitated by such switchings may be reduced to a minimum.

In carrying out the invention, use is made of multiple winding inductance units of the kind in which the body of the inductance unit, which body carries the windings, is movably mounted, the windings terminating in contact devices which are associated selectively with co-operating contact devices, according to the position into which the said body is moved.

According to this invention a multi-range radio or other high frequency receiver comprises a plurality of movably mounted inductance units, each having a plurality of sets of windings (each set of windings being appropriate to one tuning range), the windings of each unit terminating in contact devices adapted to co-operate selectively with appropriate switch members, according to the position into which the unit is moved, and means are provided for actuating all said units in common, so that by operating the common actuating means all said units may be moved together into positions in which the windings in circuit are all appropriate to a desired wave length range.

The invention is illustrated in the drawings accompanying the specification in which Figure 1 is a simplified wiring diagram of an amplifier, suitable for use in connection with a direction finding installation; Figure 2 is a schematic elevation showing the mechanical arrangement for operating the multi-winding inductance units employed in the amplifier shown in Figure 1; Figure 2a is an elevation similar to that of Figure 2; Figure 2a, however, shows in detail a portion of the mechanical means for supporting the inductance units, and also shows the manner in which the unused inductances are short circuited; Figure 3 is a sectional view looking at the end of the inductance carrying form and shows the detailed arrangement of the contact devices embodied in Figure 2; Figure 3a is a sectional view similar to Figure 3; however in Figure 3a details of the mechanism for short circuiting the unused windings of the inductance units is shown; and Figure

4 is an end view of Figure 2 showing the common control knob and associated pointer.

Referring to the drawings, input signals received at I are applied through a transformer between the control grid and cathode of a high frequency amplifying screened grid valve V1. The transformer consists of two portions; a primary portion 2 and a secondary portion 4. On the primary portion are provided three primary windings 1, 3 and 5, the winding 1 terminating in contacts C2, and C3, and the winding 3 terminating in contacts C1 and C4. The winding 5 also terminates in contacts as shown but in order to simplify the description of my novel inductance changing system, two different transformer systems only will be described. The manner in which the additional transformer systems are placed in circuit will be apparent from the description given in connection with the two transformer systems. The secondary portion 4 similarly carries three windings 6, 8 and 10, of which 6 and 8 terminate respectively in contacts C6, C8 and C5 and C8. Each primary winding is appropriate to one wave length range, as also is each secondary winding. The portions 2 and 4 constitute a mechanical unit which is rotatably mounted, and fixed switch members S1, S2, S3, S4 are provided so that in the position shown in Figure 1, the windings 1 and 6 are in circuit, while, by rotating the unit comprising the portions 2 and 4, the windings 3 and 8 or 5 and 10 may be put into circuit. Grid bias may be supplied to the control grid of valve V1 from a source of potential, not shown, in series with the selected winding or may be produced by the potential drop in resistor R in the filament lead. Grid bias may be supplied in a like manner to the second high frequency amplifying screened grid valve V2. Valve V1 is coupled to valve V2 through a second similar transformer having primary and secondary portions 14 and 16 respectively. The arrangement of this transformer is similar to that already described, the primary windings being indicated at 13, 15, and 17, and the secondary windings being indicated at 13', 15', and 17', while the contacts are indicated at C9 . . . C16, and the co-operating switch members at S5 . . . S8.

Valve V2 is coupled to a detector valve V3 through a further transformer which, so far as the transformer portion is concerned, is similar to the transformers already described. Mechanically, however, the unit differs from the two transformer units above described in that it com-

- prises in addition to a primary portion 20 and a secondary portion 22, a reaction portion R. The windings on the transformer primary and secondary portions are indicated at 19, 21, 24, 26; 5 the fixed contacts of these portions are indicated at C17 . . . C24, and the co-operating switch members are indicated at S9 . . . S12. The reaction portion R, which, as will be seen from Figure 2, is in a mechanical unit with the portions 10 20 and 22, is provided with windings 23, 25, each appropriate to one wave length range, the said windings terminating respectively in contacts C26, C27 and C25, C28, and co-operating with these contacts are switch members S13, S14.
- 15 The mechanical arrangement of the inductance unit comprising the portions 20, 22 and R, will be apparent from Figures 2, 3, and 4, the said unit being adapted to be rotated in common with the other units by the rotation of a common control knob CK fast on a shaft CS and driving the various mechanical units through bevel wheels, such as BW. A pointer IP is provided to indicate the wave length setting at any particular time.
- 20 Reverting to Figure 1, grid bias is applied to the valve V3 from a suitable source of potential, not shown, which is connected at GB2, while grid bias is applied to a low frequency amplifier valve V4 from a suitable source connected at GB3.
- 25 The common high tension supply point for all four valves is indicated at HT. The signal output terminals are indicated at O, the earth point at E, the common negative point at COM— and the point of application of potential for the screening electrodes of the screened grid valves at SG. Filament heating potential for all the valves is applied between LT+ and COM—, the positive filament lead including a switch LTS and a control rheostat FR.
- 30 It will be seen that with this arrangement, it is merely necessary to rotate the knob CK to bring the set from one wave length receiving range to another, while the amount of external wiring is very small, indeed, hardly more than would be 35 the case in a set designed for use on one wave length range only.
- 35 In cases in which it is desired to place adjacent inductance units at a particular angle with relation to one another e. g. at 90°, for example, to reduce magnetic coupling effects, it is merely necessary to arrange the mechanical drive from the common knob CK so as to be adapted to this end.
- 40 It will be noted that in Figures 1 and 2, three sets of windings for covering only three wave length ranges have been shown for the sake of 45 simplicity in the said figures. Obviously, however, accommodation may be made for any number of wave length ranges likely to be required in practice.
- 45 As has been set forth the amplifier represented in Figure 1 is adapted for use on three wavelength ranges although more wavelength ranges could be used. In any case screening is provided for the inductance devices in the various stages. The screens are indicated by broken lines enclosing the inductance units. It will further be noted that provision is made in Figure 1 for adapting 50 the amplifier to receive either continuous wave signals or spark signals. To this end the winding 19 is tapped and a switch is provided as shown, the circuit being such that when the switch is in its upper position (contact CW) the amplifier 55 is adapted for use for continuous wave reception

while when the switch is in its lower position (contact SP) the amplifier is adapted for use for spark reception.

The invention is obviously capable of considerable detailed variation from the arrangement without departing from the scope thereof. For example, the transformer units, the windings of which may conveniently be wound upon formers of solid insulating material, may be so constructed that each transformer may be removed from the receiver as a unit complete with its bevel wheel which is adapted to be engaged for adjustment purposes by an appropriate bevel wheel on the control shaft CS.

Another and a preferred detail modification 15 consists in providing one or more short circuiting means associated with each transformer unit in such manner that the winding or windings adjacent those actually in circuit when the transformer is in any given position of adjustment is 20 or are short circuited. This preferred arrangement presents the advantage that undesirable resonance in "idle windings" are to a large extent avoided if not completely eliminated. Such short circuiting of non-connected windings may 25 be effected in a variety of simple ways, for example, by providing, as shown in Figures 2a and 3a, stationary bridge pieces SB supported as shown and adapted to co-operate with any or all of the transformer contacts not actually contacting at any given position of adjustment with the contact devices in the circuit proper. Short circuiting means as shown in Figures 2a and 3a may be provided for each set of windings in each 30 unit in each modification of the inductance system.

Having now particularly described and ascertained the nature of my said invention and in what manner the same is to be performed, I declare that what I claim is:—

1. A multi-range oscillatory energy receiver comprising a plurality of inductance units each having a plurality of sets of coaxial windings, each set of windings being appropriate to one tuning range, the windings of each set terminating in 45 contact devices adapted to co-operate selectively with appropriate switch members according to the position into which the unit is rotated, means for rotating all of said units simultaneously and equal amounts whereby said units may be moved together into positions in which the windings in circuit are all appropriate to a desired wave length range, and means for short circuiting one or more idle windings on the inductance units.

2. A multi-frequency range tuning device comprising a plurality of sets of coupling inductances of different values, each of said sets of coupling inductances being appropriate to a different frequency range, relatively fixed rotatable supports mounted one within the other for said inductances, contacts connected to said inductances and carried by the outer one of said supports, and fixed contacts adjacent said supports in the path of rotation of said first named contacts, whereby selective connection between 60 said inductances and said fixed contacts may be made as said support is rotated.

3. A multi-frequency range tuning device comprising a plurality of sets of coupling inductances of different values, each of said coupling units 70 comprising inductances, one of which serves as a primary winding, and the other of which serves as a secondary winding, each set being appropriate to a different frequency range, rotatable telescoped supports for said inductances, contacts 75

connected to each of said inductances, said contacts being carried on the periphery of the outer of said supports, and fixed contacts adjacent said support in the path of rotation of said first named contacts whereby rotation of said support produces selective connection between said sets of inductances and said fixed contacts by way of said contacts on said support.

4. In a multi-range tuning device, a plurality of sets of coupling inductances, each of said sets of coupling inductances comprising a primary winding and a secondary winding, and a reaction winding, said windings of each set being coupled and being appropriate to a different frequency range, rotatable supports one within the other for each set of said inductances, contacts connected to each of said windings, said contacts being carried on the periphery of the outer of said supports, and fixed contacts adjacent said supports in the path of rotation of said first named contacts whereby rotation of said support produces selective connection between the windings of said sets of inductances and said fixed contacts.

5. A multi-frequency range tuning device comprising, a plurality of sets of coupling inductances of different values, each of said sets of coupling inductances being appropriate to a particular frequency range, relatively fixed rotatable supports mounted one within the other for said inductances, contacts connected to said inductances and carried by the outer one of said supports, fixed contacts adjacent said supports in the path of rotation of said first named contacts, whereby selective connection between the inductances in each set of said inductances and said fixed contacts may be made as said support is rotated, and conductive elements adjacent said support in the path of rotation of said first named contacts to short circuit one or more of the inductances not selectively connected with said fixed contacts.

6. A multi-frequency range tuning device comprising a plurality of inductances of different inductive values, each of said inductances being appropriate to a particular frequency range, a rotatable support for said inductances, contacts connected to each of said inductances and carried by said support, fixed contacts adjacent said support in the path of rotation of said first named contacts, whereby selective connection between each of said inductances and said fixed contacts may be made as said support is rotated, and conductive elements adjacent said support in the path of rotation of said first named contacts to short circuit one or more of the inductances not connected with said fixed contacts.

7. A multi-frequency range tuning device comprising a plurality of tuning inductances of different inductive values, each of said tuning inductances being appropriate to a particular frequency range, a cylindrical rotatable support for said inductances, contacts on the periphery of said support, connections between the inductances carried by said support and said contacts, fixed contacts adjacent said support in the path of rotation of said first named contacts, whereby selective connection between each of said inductances and said fixed contacts may be made as said support is rotated, and conductive elements adjacent said support in the path of rotation of said first named contacts to short circuit one or more of the inductances.

8. A multi-frequency range tuning device comprising a plurality of sets of tunable coupling inductances of different values, each of said sets

of coupling inductances comprising a pair of co-axial windings, the pairs of windings each being appropriate to a different frequency range, a rotatable support for said sets of inductances, contacts connected to each winding of each set of inductances, said contacts being carried on the periphery of said support, fixed contacts adjacent said support in the path of rotation of said first named contacts whereby rotation of said support produces selective connection between said sets of inductances and said fixed contacts by way of said contacts on said support, and conductive elements located in the path of rotation of said contacts on said supports to short circuit the sets of inductances not selected.

9. A multi-frequency range tuning device comprising a plurality of sets of coupling inductances of different values, each of said coupling inductances comprising co-axial windings and being appropriate to a different frequency range, a rotatable support for all of said inductances, contacts connected to each of said sets of inductances, said contacts being carried on the periphery of said support, fixed contacts adjacent said support in the path of rotation of said first named contacts whereby rotation of said support produces selective connection between said sets of inductances and said fixed contacts by way of said contacts on said support, conductive elements located in the path of rotation of said contacts on said supports to short circuit the inductances not selected, and means for rotating said support.

10. In a multi-range tuning system, a rotatable support, a plurality of sets of coupling inductances mounted on said support for rotation with said support, each set of coupling inductances comprising a plurality of windings each adapted to interconnect adjacent stages in a cascaded wave relay, contacts connected with said windings and extending from the periphery of said support, there being a set of contacts for each winding in each set of coupling inductances, fixed contacts mounted adjacent the periphery of said support whereby rotation of said support selectively connects the windings of said sets of coupling inductances to said fixed contacts, and conductive means mounted adjacent said support for short-circuiting one or more of the windings not connected to said aforesaid fixed contacts.

11. In a multi-range tuning system, a rotatable cylindrical support, a plurality of sets of coupling inductances mounted on axes parallel with the axis of said support for rotation with said support, each set of coupling inductances comprising a plurality of windings each adapted to interconnect adjacent stages in a cascaded wave relay, contacts connected with said windings and extending from the periphery of said support, there being a set of contacts for each winding in each set of coupling inductances, and fixed contacts mounted adjacent the periphery of said support whereby rotation of said support selectively connects the windings of said sets of coupling inductances to said fixed contacts.

12. In a multi-range tuning system, a rotatable support, a plurality of sets of coupling elements mounted on said support for rotation with said support each set of coupling elements comprising a plurality of sets of coupling windings, each set of coupling windings being adapted to interconnect adjacent stages in a cascaded wave relay, contacts connected with each winding in each

set of windings and extending from the periphery of said support, and fixed contacts mounted adjacent the periphery of said support whereby rotation of said support selectively connects 5 windings of said sets of coupling elements to said fixed contacts.

13. A tuning system as recited in claim 10 in which said contacts extending from said rotatable support are arranged in rows parallel with the 10 axes of rotation of said support and in which said fixed contacts mounted adjacent said support are also arranged in rows.

14. In a radio set a plurality of coils each adapted for use in connection with the tuning of 15 the set over a different range of signals, and a

switch device operable selectively to connect and disconnect each coil as desired for operation as a part of the set and selectively to prevent any coil not in operation from interfering with the coil in operation.

15. In a radio set, a plurality of coils each adapted for use in connection with the tuning of the set over a different range of signals, and a switching device operable selectively to connect and disconnect each coil as desired for operation 10 as a part of the set and selectively to short circuit one or more coils not in operation to thereby prevent the same from interfering with the coil in operation.

FRED WOODS. 15
